HYDRANT APPLIANCE

Anthony Scillia, Montclair, N. J.

Application August 5, 1937, Serial No. 157,482

6 Claims. (Cl. 137—13)

My invention relates to an appliance for use in connection with fire hydrants of the type used in municipal water systems.

Such hydrants are provided with valves actuated by turning a stem-nut which is centrally disposed in the hydrant "top" or "bonnet", the stem-nut threadedly engaging the valve stem.

Frequently the valve seat plate "sticks" or "freezes" to its seat ring, and considerable force must be applied to free it. When such force is applied at the stem-nut, the result is that the valve stem becomes distorted, as it bears the entire strain, and in many cases the valve stem has actually broken away from the other parts. The danger of this condition in a fire hydrant is obvious.

The object of my invention is to provide an appliance which is adapted to immediately and effectively release a "frozen" or "stuck" valve seat plate by a novel arrangement which does not strain the valve stem and permits the application of all of the force required without danger of straining or distorting the valve parts. The same appliance enables the valve seat plate to be fully threaded to the seat ring to obviate the danger of leakage.

These and other advantageous objects, which will later appear, are accomplished by the simple and practical construction, combination and arrangement of parts hereinafter described and shown in the accompanying drawing, forming part hereof, and in which:

Fig. 1 is a vertical sectional view of a hydrant with its top removed, showing the appliance of my invention in position for actuating the hydrant valve,

Fig. 2 is a side elevational view of the appliance of my invention,

Fig. 3 is a transverse sectional view taken on line 3—3 of Fig. 1 in the direction of the arrows,

Fig. 4 is a transverse sectional view taken on line 4—4 of Fig. 1 in the direction of the arrows,

Fig. 5 is a perspective view of the lower portion of the appliance of my invention, and

Fig. 6 is a view corresponding to that shown in Fig. 3, but of a modified form of my invention.

In Fig. 1 of the drawing, the appliance 10 of my invention is shown in engagement with the valve 12 of the hydrant 11.

The hydrant 11 comprises a barrel 13 having a nozzle N; a "bonnet" or "cover" member is removably secured to the upper end 14 of the barrel in any convenient conventional manner. The barrel 13 is provided with a circumferential flange 16 at the lower end thereof which is se-

cured, by bolts 17 or the like, to a similar flange 16' of the hydrant shoe 18, the latter having an open end 19 for connection with a water supply system.

The hydrant valve 12 has an elongated stem 20, the upper, threaded end 21 of which is normally received within a threaded stem-nut 41 which is normally centrally arranged in and projects above the hydrant cover; by rotating the stem-nut 41 the hydrant valve is normally lowered or raised to open or close the valve. The valve 12 is arranged on the lower end of the stem 20, said valve comprising a washer unit 22 clamped between clamping plates which have threaded engagement with each other and are held on the lower end of the valve stem 20 by nut 25 and lock nut 26. The structure described in this paragraph is well-known in the art.

The valve 12 is further provided with a seat plate 27 against which the washer unit 22 is firmly clamped when the valve is closed, said plate having studs 27' which support a yoke having vanes 28. The plate 27 is adapted to threadedly engage the ring 42 and normally closes the drains 30 of said ring.

The plate 27 frequently "sticks" or "freezes" to the ring 42, with the result that considerable force must be applied to free it. When this force is applied in the usual manner to the stem nut 41 in the hydrant cover, the stem becomes distorted and frequently the vanes 28 become broken as a result. The appliance 10 of my invention is designed to quickly relieve the "stuck" or "frozen" condition without endangering or straining any of the parts.

The valve washer unit 22 seats against the underside of plate 27; if plate 27 is not fully threaded to ring 42 a seepage of water occurs between plate 27 and ring 42. My invention is designed to relieve this condition by enabling the plate 27 to be fully threaded to the ring 42 by the exertion of all the force required for this purpose without straining the valve stem or any of the other parts.

In using my invention the valve stem nut 41 and the "bonnet" or "cover" of the hydrant are removed in the usual manner.

The appliance 10 of my invention comprises an elongated hollow tube 31 adapted to be slipped over the valve stem 20, said tube having an enlarged head 32 at the lower end thereof said head having a squared portion 33 adapted to register with the squared portion 34 of the valve stem. The head 32 is provided with a down-

turned portion 35 provided with recesses 36 adapted to register with and receive the vanes 28 of the plate 27. The tube 31 is provided with means for aligning the same within the barrel 11 5 and to enable the same to be easily rotated therein. Said means may comprise a ring 37 secured to the tube by studs 38 or the like, as shown in Figs. 1 and 3, or, as in Fig. 6, the ring 37 may be dispensed with and the studs 38 slightly elongated to serve the same purpose. 10

The tube 31 is provided at its upper end with an open socket 42 provided with an internal ring 43.

The threaded upper end 21 of the valve stem 15 is passed through the ring 43 of socket 42 and the stem nut 41 which was previously removed from the hydrant is then threaded to the end 21 of the valve stem until said stem nut bears against the ring 43 and the valve has been firmly 20 drawn up and seated. Then by merely turning the grip member 40 at the upper end of appliance 10 the plate 27 may be fully threaded to the ring 42, in cases where there has been leakage between plate 27 and ring 42, or, where the plate 25 27 is "frozen" or "stuck" to the ring 42, the grip member 40 is turned in the other direction to disengage the plate 27 from the ring 42.

After the appliance 10 has served its function, the stem nut 41 is disengaged from the stem 21, 30 appliance 10 is removed from the hydrant and the "bonnet" or "cover" member (with the stem nut) replaced; by turning the stem-nut the valve may be re-seated in the hydrant in the usual manner.

35 The foregoing description is to be regarded as descriptive and illustrative only and not as restrictive of or limitative of the invention, of which obviously many modifications may be made embodying the invention and without departing 40 from the spirit and scope of the invention as set forth in the annexed claims.

Having thus described my invention, what I claim as new and desire to secure by Letters Patent, is:

45 1. An appliance of the character described comprising an elongated hollow tube provided at its lower end with a head having a downturned portion provided with recesses adapted to register with and receive the vanes of a hydrant valve 50 plate, and gripping means at the upper end of said tube for turning the same to engage the vanes and actuate the plate, said head having an

internally squared portion adapted to register with an externally squared portion of the valve stem.

2. An appliance of the character described comprising an elongated hollow tube provided at 5 its lower end with a head having means for engaging vanes of a hydrant valve plate, said head having an internal non-circular portion adapted to register with an external non-circular portion of the valve stem.

3. An appliance of the character described comprising an elongated hollow tube provided at 10 its lower end with a head having means for engaging vanes of a hydrant valve plate, said head having an internal non-circular portion adapted 15 to register with an external non-circular portion of the valve stem, said tube being provided with peripheral means for engaging the inner walls of hydrant barrel, to align the same therein and enable the same to be easily rotated therein. 20

4. An appliance of the character described comprising an elongated hollow tube provided at its lower end with a head having means for engaging vanes of a hydrant valve plate, said head having an internal non-circular portion adapted 25 to register with an external non-circular portion of the valve stem, a ring of slightly less diameter than the interior of a hydrant barrel secured to said tube for aligning the tube within the hydrant barrel and for enabling the same to be 30 easily rotated therein.

5. An appliance of the character described comprising an elongated hollow tube provided at 35 its lower end with a head having means for engaging vanes of a hydrant valve plate, said head having an internal non-circular portion adapted to register with an external non-circular portion of the valve stem, and studs radially secured to said tube for aligning the tube within a hydrant barrel and for enabling the same to be easily ro- 40 tated therein.

6. An appliance of the character described comprising an elongated hollow tube provided at its lower end with a head having means for engaging vanes of a hydrant valve plate, said head 45 having an internal non-circular portion adapted to register with an external non-circular portion of the valve stem, an open ring secured within the tube at the upper end thereof and an open socket above said ring adapted to receive a mem- 50 ber for engagement with said stem and ring.

ANTHONY SCILLIA.
